PNEUMATIC DISPATCH SYSTEM

Fred R. Taisey, Lowell, Mass., assignor to The Lamson Company, Syracuse, N. Y., a corporation of Massachusetts

Application November 7, 1930. Serial No. 493,927

23 Claims. (Cl. 243—28)

This invention relates to an improvement in pneumatic dispatch systems, and more particularly to a gate or similar means for closing a carrier transit passage therein, which gate under the impact of a carrier traveling through the passage yields, opening the passage and permitting the continuance of the travel of the carrier therethrough.

Such a gate is of value especially in systems where the carriers are impelled by air pressure to close the passage and prevent entry or escape of air except when a carrier is actually in transit through the passage. The device is particularly applicable at the terminals of the system, permitting the introduction or the ejection of a carrier and at the same time limiting to a minimum the entry or escape of the air which is of necessity attendant upon such introduction or ejection.

Heretofore gates have been provided at the mouths of the terminals, usually in the form of doors or clapper valves. In one form of delivery terminal the gate is opened by the impact of the carriers as they are discharged and, being a unitary plate hinged to the terminal, is accordingly swung wide open, permitting entry or escape of considerable air. In another form of delivery terminal the door is opened manually when the arrival of a carrier at the terminal has been indicated audibly or otherwise. In the form of gate-equipped dispatch terminal most commonly used the clapper valve must be raised before the carrier can be introduced and this is usually a manual operation, although occasionally the end of the carrier is used. Since the clapper valve is usually a plate hinged at one end to the mouth of the terminal similar to the clapper valve at the delivery terminal above mentioned, it will be open to the same objection.

The primary object of this invention is to provide in the carrier transit passage of a pneumatic dispatch system a gate which is normally closed and which is opened by the impact of the traveling carrier, said gate including two or more relatively movable plates which are in contact when the gate is closed.

A further object of this invention is to provide a gate including in addition to the relatively movable plates a tube, the walls of which define the passage and with which the plates contact when in the closed position, and means for carrying the plates, which means are pivotally supported and which the carrier in transit impacts to open the gate.

Other objects of the invention will appear from a consideration of the following specification

taken in connection with the drawing which forms a part thereof and in which is illustrated the application of this invention to a dispatch or inlet terminal of a pneumatic dispatch system.

In the drawing:

Fig. 1 is a plan view of a dispatch terminal embodying this invention;

Fig. 2 is a longitudinal sectional view, on a larger scale, taken along the line 2—2 of Fig. 1 and showing the terminal with the gate closed;

Fig. 3 is a view similar to Fig. 2 illustrating the terminal with the gate open, a carrier having been partly introduced;

Fig. 4 is a sectional view taken along the line 4—4 of Fig. 3, the valve plates being omitted; and

Fig. 5 is a view similar to Fig. 2 but on a smaller scale illustrating a receiving terminal embodying this invention.

The dispatch terminal selected for illustration of one embodiment of this invention is a fitting which may be a stamping or casting substantially rectangular in conformation, as shown in Figs. 1 and 4, and which comprises an outer casing 10, an upper tube 11 and a lower tube 12. The tubes 11 and 12 here shown are circular and of the same diameter arranged in alignment, as illustrated in Figs. 2 and 3 of the drawing, so that the walls thereof define the transit carrier passage 13. The terminal is mounted upon the end of a transit tube 14 in the usual manner. In the walls of the upper tube 11 are formed diametrically opposed slots 15 through which are free to travel straps 16 pivotally mounted at their upper ends upon rods 17. The lower end 18 of each strap 16 is bent substantially at right angles to the body of the strap and to it is secured a plate 20 which will hereafter be referred to as a valve plate. As shown particularly in Figs. 2 and 3, the valve plates 20 are free to reciprocate in the space 21 between the upper and lower tubes. The lower tube 12 terminates at its upper end in a pair of inclined seats 22 against which the valve plates 20 rest when the passage is closed and the terminal is not in use (see Fig. 2). Suitably formed springs 23 are provided to hold the plates normally in the position shown in Fig. 2 with abutting edges in contact and resting upon the seats 22 so that the gate which comprises the plates and associated elements closes the passage 13.

The straps 16 when the gate is closed project into the path of travel of a carrier and under impact of the carrier are forced outwardly into the casing 10 to permit the carrier to advance through the passage 13 into the transit

tube 14. This operation is clearly shown in Fig. 3 of the drawing in which a carrier 25 is shown partially introduced into the mouth of the terminal, and the valve plates 20 are accordingly removed from their normal positions so that the carrier can be without difficulty introduced into the transit tube. As soon as the carrier passes the straps 16, the plates will be quickly returned to the normal position and the 10 gate will close the passage 13.

In Fig. 5 is illustrated a receiving terminal 30 to which carriers are supplied by a transit tube 31 and from which the carriers are delivered through an outlet 32. A by-pass is provided in 15 the usual manner which connects with the tube 31 through opening 33 above the valve plates 35. The plates 35 normally close the passage from the tube 31 to the outlet 32 and are supported upon straps 36 with which the heads of the arriving carriers contact so that the plates 35 are separated and the carriers pass on to the outlet 32.

It will be understood that various changes in form and construction may be made as, for example, the casing 10 may be integral with one or both tubes or the tubes may be oval or rectangular to provide a passage which will conform with the contour of the carriers to be transported by the system. Moreover, while the invention has been shown and described as applied to a dispatch or inlet terminal, it is not limited thereto but may be applied to a delivery or outlet terminal or elsewhere throughout the system wherever it is desired to employ a gate normally closing the transit carrier passage, which gate is opened by the impact of a carrier in transit, without departing from the spirit and scope of the invention as set forth in the following claims.

I claim:

40 1. In a pneumatic dispatch system including a transit tube through which a carrier may travel, a casing including two longitudinally spaced tubes in alignment with said transit tube and forming a passage thereto through the casing and a gate in said casing normally closing said passage and including a pair of separable plates which in contact with one of said casing tubes close the passage, and which separate under impact upon the gate of a carrier traveling through the passage to permit the continuance of such travel.

45 2. In a pneumatic dispatch system including a transit tube through which a carrier may travel, a casing including two longitudinally spaced tubes in alignment with said transit tube and forming a passage thereto through the casing and a gate in said casing normally closing said passage and including a pair of separable plates which in contact with one of said casing tubes close the passage, and a pair of straps pivotally mounted at one end to the other of said casing tubes and to the other end of which said plates are secured, said plates being adapted to separate under impact upon the straps of a carrier traveling through the passage to permit the continuance of such travel.

50 3. In a pneumatic dispatch system, including a transit tube through which a carrier may travel, a casing including two longitudinally spaced tubes in alignment with said transit tube and forming a passage thereto through the casing and a gate comprising separable means supported by one tube for normally engaging the other tube 55 and closing said passage, which means are automatically shifted to open the passage by contact with a carrier traveling therethrough.

4. In a pneumatic dispatch system, including a transit tube through which a carrier may travel, a casing including two longitudinally spaced tubes in alignment with said transit tube and forming a passage thereto through the casing and a gate comprising relatively movable separable means supported by one tube for normally 80 engaging the other tube and closing said passage, which means are automatically shifted to open the passage by contact with the tube supported portion of a carrier traveling therethrough.

5. In a pneumatic dispatch system, including a transit tube through which a carrier may travel, a casing including two longitudinally spaced tubes in alignment with said transit tube and forming a passage thereto through the casing, one of said tubes having longitudinal slots extending from the inner end thereof, and a gate comprising straps movable in the slots of one tube and a pair of means carried by said straps and movable relatively to each other and to the passage for normally closing said passage at the inner end of the other tube, which means are 90 automatically shifted to open the passage by contact with the straps of a carrier traveling through the slotted tube into the casing passage.

6. In a pneumatic dispatch system, including a transit tube through which a carrier may travel, a casing including two longitudinally spaced tubes in alignment with said transit tube and forming a passage thereto through the casing, one of said tubes having longitudinal slots extending from the inner end thereof and a gate in said casing 100 normally closing said passage at the inner end of the other tube and including straps supported by said slotted tube and movable in the slots thereof and separable plates carried by said straps and relatively movable, which plates separate under impact upon the straps of a carrier traveling through the slotted tube into the casing passage to permit the continuance of such travel.

7. In a pneumatic dispatch system, including a transit tube through which a carrier may travel, a casing including two longitudinally spaced tubes in alignment with said transit tube and forming a passage thereto through the casing, one of said tubes having longitudinal slots extending from the inner end thereof and a gate in said casing 110 normally closing said passage at the inner end of the other tube and including straps supported by said slotted tube and movable in the slots thereof and a pair of separable plates carried by said straps and relatively movable and means for holding said plates in contact across the passage, which plates separate under impact upon the straps of a carrier traveling through the slotted tube into the casing passage to permit the continuance of such travel.

8. In a pneumatic dispatch system, including a transit tube through which a carrier may travel, a casing including two longitudinally spaced tubes in alignment with said transit tube and forming a passage thereto through the casing, one of said tubes having longitudinal slots extending from the inner end thereof and a gate in said casing 120 normally closing said passage at the inner end of the other tube and including straps supported by said slotted tube and movable in the slots thereof and separable plates carried by said straps and relatively movable which plates meet across the passage and close the same, and which separate under impact upon the straps of a carrier traveling through the slotted tube into the casing 125

- passage to permit the continuance of such travel.
9. In a pneumatic dispatch system, in combination with a transit tube of a terminal comprising a casing having a passage therein through which a carrier may travel, a tube, the walls of which define a portion of said passage, said tube having inclined seats at one end and resting at the other end upon the end of the transit tube to form a continuation thereof and a gate normally closing said passage and including plates movably mounted in said casing which normally coact with the tube seats to close the passage, said plates being automatically shifted to open the passage under impact upon the gate of a carrier traveling therethrough.
10. In a pneumatic dispatch system, in combination with a transit tube of a terminal comprising a casing having a passage therein through which a carrier may travel, a tube, the walls of which define a portion of said passage said tube having inclined seats at one end and resting at the other end upon the end of the transit tube to form a continuation thereof, a gate normally closing said passage and including plates pivotally supported within said casing and movable relative to each other, and means for holding said plates normally in contact with the tube seats to close the passage, said plates being automatically separated from the seats to open the passage under impact upon the gate of a carrier traveling therethrough.
11. In a pneumatic dispatch system, in combination with a transit tube of a terminal comprising a casing having a passage therein through which a carrier may travel, a tube, the walls of which define a portion of said passage said tube having inclined seats at one end and resting at the other end upon the end of the transit tube to form a continuation thereof, a gate normally closing said passage and including plates pivotally supported within said casing and movable relative to each other, and means for holding said plates normally in contact with each other and with the tube seats to close the passage, said plates being automatically separated from each other to open the passage under impact upon the gate of a carrier traveling therethrough.
12. In a pneumatic dispatch system, in combination with a transit tube of a terminal comprising a casing having a passage therein through which a carrier may travel, a tube, the walls of which define a portion of said passage said tube having inclined seats at one end and resting at the other end upon the end of the transit tube to form a continuation thereof, a gate normally closing said passage and including valve plates, movable straps by which said plates are supported within said casing, and means for holding said plates normally in contact with the tube seats to close the passage, said plates being separated from the seats to open the passage under impact upon the straps of a carrier traveling therethrough.
13. In a pneumatic dispatch system, in combination with a transit tube of a terminal comprising a casing having a passage therein through which a carrier may travel, a tube, the walls of which define a portion of said passage said tube having inclined seats at one end and resting at the other end upon the end of the transit tube to form a continuation thereof, a gate normally closing said passage and including valve plates, straps each pivotally supported at one end within said casing and carrying one of said plates at the other end, and means for holding said plates normally in contact with the tube seats to close the passage, said plates being separated from the seats to open the passage under impact upon the straps of a carrier traveling therethrough.
14. In a pneumatic dispatch system, in combination with a transit tube of a terminal comprising a casing having a passage therein through which a carrier may travel, a tube, the walls of which define a portion of said passage said tube having inclined seats at one end and resting at the other end upon the end of the transit tube to form a continuation thereof, a gate normally closing said passage and including valve plates, straps each pivotally supported at one end within said casing and carrying one of said plates at the other end, and means acting upon the straps for holding said plates normally in contact with each other and with the tube seats to close the passage, said plates being separated from each other and from the seats to open the passage under impact upon the straps of a carrier traveling therethrough.
15. In a pneumatic dispatch system, in combination with a transit tube of a dispatch terminal comprising a casing including a pair of longitudinally spaced tubes, the walls of which are in alignment with the transit tube to define a passage through which a carrier may be introduced into the transit tube, and a gate normally closing said passage and comprising separable plates movably supported by one of said tubes and in contact with the other of said tubes when in the closing position, said plates being separated upon the introduction of a carrier into the passage.
16. In a pneumatic dispatch system, in combination with a transit tube of a dispatch terminal comprising a casing including a pair of longitudinally spaced tubes, the walls of which are in alignment with the transit tube to define a passage through which a carrier may be introduced into the transit tube, a gate normally closing said passage and comprising separable plates, straps pivotally supported by one of said tubes and to which straps the plates are secured, and means to hold said plates yieldably in contact with the other of said tubes when in closing position, said plates being separated upon the introduction of a carrier into the passage by the impact of the carrier with said straps.
17. In a pneumatic dispatch system, in combination with a transit tube of a dispatch terminal comprising a casing including a pair of longitudinally spaced tubes, the walls of which are in alignment with the transit tube to define a passage through which a carrier may be introduced into the transit tube, a gate normally closing said passage and comprising separable plates, straps pivotally supported by one of said tubes and to which straps the plates are secured, and means acting upon said straps to hold said plates yieldably in contact with the other of said tubes when in closing position, said plates being separated upon the introduction of a carrier into the passage by the impact of the carrier with said straps.
18. In a pneumatic dispatch system the combination with a transit tube of a dispatch terminal comprising a casing including a pair of longitudinally spaced tubes, the walls of which are in alignment with the transit tube to define a passage through which a carrier may be introduced into the transit tube, a gate normally closing said passage and comprising separable plates, and straps pivotally supported by one of said tubes, and to which straps the plates are secured, the other of said tubes being provided at its inner end with inclined seats, and means to hold the plates yieldably in contact with the tube seats to close the passage, said plates being separated from the seats to open the passage under impact upon the straps of a carrier traveling therethrough.

ably in contact with the seats when in closing position, said plates being separated from the seats upon the introduction of a carrier into the transit tube by the impact of the carrier with said straps.

19. In a pneumatic dispatch system the combination with a transit tube of a dispatch terminal comprising a casing including a pair of longitudinally spaced tubes, the walls of which are in alignment with the transit tube to define a passage through which a carrier may be introduced into the transit tube, a gate normally closing said passage and comprising separable plates, and straps pivotally supported by one of said tubes, and to which straps the plates are secured, the other of said tubes being provided at its inner end with inclined seats, and means to hold the plates yieldably in contact with the seats and with each other when in closing position, said plates being separated from the seats and from each other upon the introduction of a carrier into the transit tube by the impact of the carrier with said straps.

20. In a pneumatic dispatch system the combination with a transit tube of a dispatch terminal comprising a casing including a pair of longitudinally spaced tubes, the walls of which are in alignment with the transit tube to define a passage through which a carrier may be introduced into the transit tube, one of said tubes having therein longitudinal slots extending from the inner end thereof and the other of said tubes being provided at its inner end with inclined seats, and a gate normally closing the passage and comprising separable plates, straps pivotally supported by the slotted tube to swing through the slots therein and to which straps the plates are secured, and means to hold the plates yieldably in contact with the tube seats when in closing position, said plates being separated from the seats upon the introduction of a carrier into the transit tube by the impact of the carrier with said straps.

21. In a pneumatic dispatch system the combination with a transit tube of a dispatch terminal comprising a casing including a pair of longitudinally spaced tubes, the walls of which are in alignment with the transit tube to define a passage through which a carrier may be introduced into

the transit tube, one of said tubes having therein longitudinal slots extending from the inner end thereof and the other of said tubes being provided at its inner end with inclined seats, and a gate normally closing the passage and comprising separable plates, straps pivotally supported by the slotted tube to swing through the slots therein and to which straps the plates are secured, and means to hold the plates yieldably in contact with the tube seats and with each other when in closing position, said plates being separated from the seats and from each other upon the introduction of a carrier into the transit tube by the impact of the carrier with said straps.

22. In a pneumatic dispatch system including a transit tube, a casing including two longitudinally spaced tubes in alignment with said transit tube and forming a passage thereto through the casing, one of said tubes having longitudinal slots extending from the inner end thereof and a gate in said casing for closing the passage therethrough said gate comprising separable plates and straps, on which said plates are mounted, pivotally supported at one end to said slotted tube and normally passing through said slots into the interior of the tube, said plates being separated upon the impact of a carrier traveling through the slotted tube upon the straps therein.

23. In a pneumatic dispatch system including a transit tube, a casing including two longitudinally spaced tubes in alignment with said transit tube and forming a passage thereto through the casing, one of said tubes having longitudinal slots extending from the inner end thereof and the other of said tubes being provided with inclined seats at the inner end and a gate in said casing for closing the passage therethrough, said gate comprising separable plates normally resting upon the tube seats and straps, on which said plates are mounted, pivotally supported at one end to said slotted tube and normally passing through said slots into the interior of that tube, said plates being separated from said seats upon the impact of a carrier traveling through the slotted tube upon the straps therein.
